UNITED STATES PATENT OFFICE.

CHARLES S. WILLIAMS, OF DENVER, ILLINOIS.

INTERNAL-COMBUSTION ENGINE.

1,217,379.

Specification of Letters Patent. Patented Feb. 27, 1917.

Application filed March 25, 1916. Serial No. 86,746.

To all whom it may concern:

Be it known that I, CHARLES S. WILLIAMS, a citizen of the United States, residing at Denver, in the county of Hancock and State of Illinois, have invented certain new and useful Improvements in Internal-Combustion Engines, of which the following is a specification:

This invention relates to an improved internal combustion engine and the principal object of the invention is to provide an engine having an improved type of fuel compression and feeding mechanism and to further provide an improved type of combustion chamber and disk carried by the engine shaft and coöperating with the combustion chambers.

Another object of the invention is to provide an improved type of driving rotors carried by the engine shaft.

Another object of the invention is to provide an improved type of baffles rigidly mounted in the engine casing between the rotors carried by the shafts.

Another object of the invention is to provide improved means for actuating the fuel compressing and feeding mechanism in timed relation to the rotation of the engine shaft.

This invention is illustrated in the accompanying drawings, wherein:

Figure 1 is a view taken along the line $a-a$ of Fig. 3.

Fig. 2 is a transverse sectional view taken along the line 2-2 of Fig. 1.

Fig. 3 is a longitudinal transverse sectional view taken along the line 3-3 of Fig. 2.

Fig. 4 is a view showing the engine shaft in cross section and one of the driving fans in elevation.

Fig. 5 is a view in elevation of the disk carried by the shaft and coöperating with the combustion chambers of the engine.

The casing 10 is provided with a head 11 having the combustion chambers 12 formed therein and provided with inlet ports 13 communicating with the cylinders 14 positioned at the sides of the casing and in their turn provided with inlet ports 15 communicating with the manifold 16 leading from a carburetor not shown. Valves 17 and 18 are provided for these ports 13 and 15 and are yieldably held in a closed position by springs 19 and 20 and opened in opposite directions so that when the ports

13 are opened for sucking gas into the cylinders 14, the valves 17 will be closed and when the gas is forced into the combustion chambers past the open valves 17, the valves 18 will be closed. Pistons 21 are slidably mounted in these cylinders 14 and carry piston rods 22 extending along the sides of the casing 10 and connected with the crank arms 23 of gears 24 rotatably mounted above and below the gears 25 carried by the horizontally extending driven shafts 26. These driven shafts 26 extend through the walls of the housing 27 fitting upon the ends of the engine casing 10 and will have their inner ends rotatably mounted in the bearings of the bearing brackets 28 as shown in Fig. 3. Gears 29 are carried by these driven shafts 26 and mesh with a gear 30 carried by the extension 31 of the engine shaft 32 and it will thus be seen that as this engine shaft rotates, rotary movement will be transmitted to the driven shafts 26 and as these driven shafts rotate, the pistons will be reciprocated in the cylinders 14 with the upper piston moving in an opposite direction to the lower piston.

The engine shaft or driving shaft 32 extends longitudinally through the casing 10 and is rotatably mounted in bearings 33 and 34 formed in the heads 11 and 35 and carries rotors 36 which resemble fans as shown in Fig. 4. These rotors are positioned between similarly constructed baffles 37 mounted in the casing 10 and held stationary therein by any suitable means. A disk 38 is mounted upon this engine shaft 32 adjacent the head 11 and is provided with slots forming passageways 39 extending diagonally through the disk and positioned for registering with diagonally disposed combustion chambers. That is to say, as the disk 38 rotates, one of the passageways 39 will be in registry with an upper combustion chamber 12 while the second is in registry with a diagonally disposed lower combustion chamber. Therefore in operation the engine will receive two impulses each revolution although four explosions occur.

In operation, the pistons will move to draw the gas into the cylinders 14 and upon the return stroke will force this gas into the combustion chambers. The gas will then be under compression and as the passageways 39 register with the combustion chambers containing the gas under pressure, the spark plugs 40 will explode the gases thus acting

upon disk 38 to rotate the engine shaft. The gases will then pass successively through the baffles 37 and through the space between the blades of the rotors 36, acting upon these rotors to rotate the shaft 32 and any machine which may be in operative connection with the extension 31 of this shaft and upon reaching the head 35 will pass through the outlet port 41.

10 I have therefore provided an engine which is rather simple in construction but at the same time will be strong and durable. I have further provided an engine which will be easy to take down to clean as the piston rods 22 can be disconnected from the crank arms 23 and the housing disconnected from casing 10. The head 35 can be removed and the rotors and baffles withdrawn from the casing and also shaft 32 thus leaving the casing clear and permitting it to be easily cleaned.

15 Having thus described the invention what is claimed is:—

20 1. An internal combustion engine comprising a casing, an engine shaft rotatably mounted in the casing and extending beyond one end thereof, said casing being provided with combustion chambers and with an outlet port, a housing at the end of said casing extending about the outer end portion of said shaft, a gear carried by said shaft, stub-shafts extending transversely through said housing and provided at their inner ends 25 with gears meshing with the gear of said engine shaft and having gears mounted upon their outer end portions, cylinders

30 positioned along said casing and having valve controlled communication with said combustion chambers, gears rotatably connected with said casing and engaging the 40 gears at the outer ends of said stub shafts, crank arms extending from said last mentioned gears, pistons slidably mounted in said cylinders and having their piston rods pivotally connected with said crank arms, 45 rotors mounted upon said engine shaft within in said casing, and means for guiding the passage of gases through said casing.

2. An internal combustion engine including a casing provided with combustion 50 chambers and with an outlet port, an engine shaft rotatably mounted in the casing and extending beyond one end thereof, a gear carried by said shaft, stub shafts extending 55 transversely of the engine shaft and provided at their inner ends with gears meshing with the gear of the engine shaft, cylinders positioned along said casing and having valve controlled communication with the combustion chambers, pistons slidably 60 mounted in said cylinders and having their piston rods extending in operative relation to the stub shafts, means for transmitting movement from the stub shafts to the piston rods, and rotors mounted upon said engine 35 shaft within said casing.

In testimony whereof I affix my signature in presence of two witnesses.

CHARLES S. WILLIAMS.
